(57) **CLAIM**

We claim the ornamental design for forklift, as shown and described.

DESCRIPTION

FIG. 1 is a rear view of a configuration for a forklift; FIG. 2 is a right view of the forklift of FIG. 1; FIG. 3 is a left view of the forklift of FIG. 1; FIG. 4 is a right, rear isometric view of the forklift of FIG. 1; and, FIG. 5 is a left, rear isometric view of the forklift of FIG. 1. In FIGS. 1-5, the broken lines indicate environmental features and form no part of the claimed design.
